DISPLAY CABINET

Stanley Grant, 2928 Preston Lane, Merrick, N.Y.

Filed Mar. 25, 1965, Ser. No. 84,438

Term of patent 14 years

(Cl. D33—19)

FIG. 4

FIG. 5

FIG. 1 is a perspective view of a display cabinet showing my design;

FIG. 2 is a front elevational view on an enlarged scale;

FIG. 3 is a side elevational view;

FIG. 4 is a top plan view; and

FIG. 5 is a rear elevational view thereof.

A side elevation view from the righthand side of FIG. 2 would be the same as FIG. 3. The entire rear surface of the cabinet is perforated as fragmentarily shown in FIG. 5.

I claim:

The ornamental design for a display cabinet, substantially as shown and described.
